UNITED STATES PATENT OFFICE.

EDWARD J. KREISS AND CHARLES F. KREISS, OF BUFFALO, NEW YORK, ASSIGNORS TO
KREISS SIGN CO., INC., OF BUFFALO, NEW YORK.

ILLUMINATED SIGN.

Application filed May 1, 1926. Serial No. 196,037.

This invention relates to an illuminated sign, and more particularly to the canopy or overhead reflector type, in which the display face of the sign panel is illuminated 5 for night advertising or display by a single source of light, housed and practically concealed within a canopy or hood which is arranged above the sign panel to reflect or concentrate the light rays directly down onto 10 the display face. In this style of sign the display face, or that wall of the panel bearing the advertising matter, provides a very desirable sign when the letters or other symbols are finished in black or a dark color, and the background is white, or of a light, contrasting color. Heretofore, the dark letters or symbols have been painted directly on the light background, but more vivid and desirable results may be obtained 15 20 by mounting raised letters, finished in black, on a white background. Signs thus constructed are especially adapted for store fronts where, through a maze of surrounding artificial lights, the display face of the sign stands out in boldness. However, when 25 the letters are raised, i. e., have a thickness, they throw or cast dark shadows on the light background which shadows blend more or less with the dark letters, making them 30 indistinct and blurred, and rendering the sign face more or less illegible and obscure. More especially is this true of a sign having many crowded or small letters.

Various attempts have been made to avoid 35 these blurring shadows, such as the provision of several sources of light directed onto the sign symbols from different angles or directions, but such arrangements have heretofore proved too expensive and impractical 40 for commercial use.

The primary object of this invention is to 45 overcome this indistinctness by forming and arranging the symbols so that the major portion of the area of the side walls thereof is exposed to the light rays. The invention resides in the combination with the single source of light, of the symbols which are so formed and arranged that the major portion of their side wall areas are exposed 50 to the light rays whereby no shadows, or substantially no shadows, will be cast upon the white background. The invention further resides in the provision of high-light borders on shadow-reducing formed letters, 55 by which the letters or symbols are sharply

defined or set off from any shadows which may be cast by the side wall areas unexposed to the light rays.

In the drawings:

Fig. 1 illustrates a fragmentary front elevation of a canopy type of sign embodying a square cut block letter with the blurring shadows cast thereby.

Fig. 2 is a vertical sectional view therethrough.

Fig. 3 is a view similar to Fig. 1 illustrating a symbol constructed in accordance with our invention.

Fig. 4 is a vertical sectional view through Fig. 3.

Fig. 5 is a view similar to Fig. 1 showing a modification of our invention.

Fig. 6 is a vertical sectional view through Fig. 5.

The sign illustrated is of the single face style adapted for being mounted on the front wall of a building, but the invention is equally applicable to a double face sign in which the sign characters are arranged on both sides of the sign panel and from which the canopy extends in opposite directions.

In the form shown, the sign comprises a character-bearing panel 1 having a canopy or reflector 2 overhanging the single display face 3 for housing a plurality of electric incandescent bulbs 4 which constitute a single source of light. These bulbs in practice are arranged from twelve to sixteen inches apart within the canopy, and are of such type and power as to throw a strong and united sheet-like beam of light which shines with exceeding brilliancy through the open bottom side of the canopy onto the display face 3, which brilliancy is enhanced by the fact that the background for the display part of the sign is white, or very light in color. The sign characters or symbols are here represented as letters which may be cut out of wood, stamped from sheet metal, or molded. These block letters vary as to thickness, but in the average store front signs the thickness of these letters is from one to two inches, so that the shadows cast would be comparatively great, and more or less blur the letters and render them indistinct. In Fig. 1, we have illustrated the ordinary block type of letter at 5, the same casting depending shadows as at 6, which illustrates the blurring and indistinctness that obtains when the letters are crowded

or reduced. The present invention includes the modification of these raised letters with respect to the source of illumination whereby the major portion of the side wall areas of the letters or symbols is exposed to the light rays so as to avoid shadows and render the symbols distinct and clear. This we accomplish in the embodiment shown by reducing the unexposed side wall areas as by shaping the lower marginal portions of the different face areas of the characters or letters, as 7, with a bevel 8, the angle of which approaches the direct rays from the source of light as near as practicable. When the degree of bevel is coincident with the source of light, as indicated in Figs. 3 and 4, then no shadows will be cast from the letter onto the white background. In practice, and according to the depth of the letters, it may not be found desirable to provide a bevel equal to the angle from which the illuminating beams are directed, in which instance the bevel will be made to approach the source of light consistent with the preservation of the boldness with which the raised letters stand out. With such a bevel a slight shadow may be cast, but the cast shadow will be more in the nature of a light or penumbra shadow which will not blur or render indistinct the legibility of the sign. Consequently, by so shaping the letters to an angle equal to, or approaching, the angle of the illuminating beams, the blurring effect of cast shadows is substantially done away with. In certain letters the lower side walls may incline directly across to the upper side walls so that the lower side walls will actually constitute the face of the letters.

Thus, the square cut block letter 5 in Fig. 1 casts a shadow which tends to close the spaces in the letter between the different face portions, as the legs and cross bar thereof. This obscurity would be added to where the characters are crowded or made on a reduced scale, or where the symbols involve more or less a network of parts. At 7, in Fig. 3, we have illustrated the letter in accordance with our invention from which the source of light throws no shadows, the angularity of the border or marginal portions of the letter being equal to and coincident with that of the light beams.

This marginal bevel of the symbol may extend through the thickness thereof as depicted in Figs. 3 and 4, or only partially so. Thus, in Figs. 5 and 6 the shadow eliminating or reducing bevel 9 of letter 10 extends only a fractional part of the thickness of the letter, from the face thereof and on an angle with the light ray, in which case a light or penumbra shadow would be cast close to the base of the letter or the point where the letter is attached to the background, with substantially no blurring ef-

fect. However, to define the letter clearly from any cast shadow, and to maintain the sharpness of outline of the letter, this small beveled margin 9 is gilded, enameled, or finished off with a light color, to produce a bordering high-light effect which distinctly defines the letter with a degree of sharpness to overcome any ill effects which the light cast shadows may tend to produce.

This border forms a clear cut high light so that the subdued or softened side of the letter has a contrasting sharpened edge which renders the letter more legible and distinct.

The light rays from the single source of light contact with the upper side wall area and more or less of the lower side wall area, according to the degree of bevel, so that the major portion of the side wall areas of the different parts of a letter is exposed to the source of light, without casting blurring and obscuring shadows, and without any additional expense either in the manufacture or the operation of the sign.

The embodiment of the invention disclosed in Figures 5 and 6 forms the subject matter of our co-pending application filed August 4, 1926, Serial No. 127,014.

We claim as our invention:

1. An illuminated sign using raised letters, comprising, in combination with a housed overhead source of light and a display panel having a light background, raised symbols mounted on the background of said panel having their lower side wall areas inclined towards the source of light substantially at the angle of the incident light ray to expose said side wall areas to the source of light and avoid symbol-blurring shadows being cast from said symbols onto said background by said source of light.

2. An illuminated sign comprising a panel, an overhead reflector containing a source of light and directing the light rays therefrom down onto the panel at a shadow-casting angle thereto, and raised letters mounted on the panel within the downwardly directed light, said letters having the lower edges of their different face portions cut on an angle which coincides with the angle of the incident light ray from the source of light.

3. An illuminated sign of the canopy type having raised letters on a light background, comprising, in combination with an overhead source of light and a light background onto which the light is downwardly directed, a plurality of block-like letters having their lower marginal portions cut through the entire thickness of the letters on an angle with the background which coincides with the angle of the incident light ray with the background.
